UNITED STATES PATENT OFFICE.

FRANCIS H. PHILLIPS, OF OLD WESTBURY, NEW YORK.

BURGLAR ALARM.

1,420,743.

Specification of Letters Patent. Patented June 27, 1922.

Application filed November 13, 1919. Serial No. 337,707.

To all whom it may concern:

Be it known that I, FRANCIS H. PHILLIPS, a subject of the King of Great Britain, residing at Old Westbury, in the county of Nassau and State of New York, have invented a certain new and useful Improvement in a Burglar Alarm, of which the following is a specification.

My invention relates to burglar alarms and 10 aims to provide means for automatically discharging a fire arm which will either scare or injure the burglar and at the same time put into operation an alarm for arousing the occupants of the house about to be entered, 15 thus thoroughly protecting the property against trespassers.

A further object of the invention is to provide a device as mentioned above having actuating means extending therefrom which 20 enables the alarm to be used in protecting various areas of properties, said apparatus being simple in structure, reliable in operation, and inexpensive to manufacture.

A further object of the invention lies in 25 the provision of a casing resembling in appearance the stump of a tree, so as to eliminate the possibility of the actuating means extending therefrom, attracting attention as to the real contents of the casing.

30 Other objects and advantages of the invention will be apparent during the course of the following description.

In the accompanying drawings forming a part of this specification and in which like 35 numerals are employed to designate like parts throughout the same,

Figure 1, is an illustrative view showing my invention in use;

Figure 2, is a central vertical section of 40 the casing;

Figure 3, is a view looking down on the casing with the top removed;

Figure 4, is a fragmentary sectional view 45 on line 4—4 of Figure 3;

Figure 5, is a detail view of the gage rod used in connection with my invention;

Figure 6, is a fragmentary front view showing the position of the gun relative to the outside of the casing; and

50 Figure 7, is a fragmentary rear view.

In the drawings, wherein for the purpose of illustration I have shown a preferred embodiment of my invention, the numeral 5 designates a substantially rectangular shaped casing which resembles in appearance the stump of a tree, thus preventing

suspicion from being aroused as to its real contents. One end of the casing is provided with a removable panel 6 which is hingedly connected with the main casing as at 7, to 60 permit access to the interior thereof. Adjacent the upper end of the casing and rigidly secured to the sides thereof is a substantially U shaped shelf or flange 8 that is disposed in a horizontal position. Spaced 65 slightly from the front end of the casing is a vertical extending upright 9 the lower end of which is seated in a longitudinally extending recess 10 while the upper end is secured within the U shaped shelf or flange 70 8. The central portion of the upright is provided with an annular recess 11 having an aperture 12 through its center that is in alignment with the opening 13 through the side of the casing. Extending between the 75 two openings and disposed therein is a tubular barrel 14, the inner end of which extends slightly within the annular recess 11 and is exteriorly screw threaded to receive the angular shaped collar 15 seated within 80 the recess. The interior of the collar is screw threaded to receive the exteriorly screw threaded breech block 16 having an opening through its center as at 17. A strip of spring metal 18 is rigidly secured to the 85 upright directly below the breech block having its upper end slightly offset from the upright, as at 19. Integrally projecting from the inner side of the offset portion 20 is a firing pin 21 adapted to register and pass 90 through the opening 17 in the breech block 16. An annular ring 22 surrounds the breech block and collar holding said parts rigidly in their respective position. A collar 23 is carried by the barrel 14, being positioned in front of the upright 9.

The hammer of the device comprises a pair of longitudinal strips of metal 24, of resilient material, being joined throughout their length. The upper end of the strips 100 are bent at a right angle, as at 25, being fixedly secured to the upper edge of the upright 9 by bolts or other suitable means. A brace strip 25' extends across the upright passing over the hammer and is attached to 105 the sides of shelving 8 in any suitable manner. The lower end of the strips extend downwardly having at their lower ends an enlarged head 26 which is adapted to abut with the head 27 attached to the outer side 110 of the offset portion 19 of the arm 18. The opposite side of the enlarged head 26 is pro-

vided with a rectangular shaped washer 28 that is spaced therefrom by the collar 29 and secured against displacement by the nut 30.

Extending across the rear upper end of the casing is a tapering shaped lever 31, the apex of which is pivotally connected with one side of the shelf 8 as at 32. The opposite end of this lever extends in close proximity to the opposite side of the casing 10 and is apertured to receive one end of the cable or rope 33. The movement of the lever is controlled by the U shaped bracket 34 which passes over the lever and is secured to the shelf adjacent its inner edge. 15 The purpose of this lever is to hold the hammer head 26 in an inoperative position, as clearly shown in Figure 2. Thus when the head is forcibly drawn upwardly the lever is placed between the head and washer 28 being held in this position by the coil spring 35. This spring has one end connected to the lever while its opposite end passes through an opening in the panel 6 of the casing and its tension is adjusted 20 by the pivoted lever 36 which when in a horizontal position interposes the coils of the spring. The cable 33 is the means employed for actuating the lever 31 and extends through an opening 37 in the forward 25 end of the casing being attached to any object at a remote distance from the casing. Thus should any trespasser come in contact with the cable a slight pressure will draw the lever forward, so as to release the hammer which through its resiliency will swing 30 downwardly with sufficient force so as to drive the firing pin 21 inwardly into contact with the cartridge 38 placed within the barrel 14, the bore of the gun being 35 so placed that at the time of its discharge the trespasser will be in the direct path of the bullet and will either be injured or scared by its discharge. In order that the actuating cable 33 may be positioned at 40 various distances from the ground, I have provided a gage rod 39 which is formed from a longitudinal strip of metal pointed at its lower end, as at 40, to facilitate its erection. Along one edge is provided a 45 plurality of spaced downwardly extending angular slots 41 for the reception of the cable 33 for the purpose specified.

A pair of switch contacts are suspended from the inner edge of one side of the shelf 8 in spaced relation, between the upright 9 and the lever 31, as indicated by the numerals 42 and 43. Running from the switch contacts are wires 44, one of said wires running direct to a bell or other annunciation 50 which may be disposed within the house which is being protected, while the other wire is interposed by a plurality of storage batteries 45 which furnish the current for ringing the bell. Pivottally attached to the 55 switch contact 43 approximately interme-

diate its length is the switch arm 46 that when extended in a vertical position is of such length as to contact with the longitudinal edge of the lever 31, as clearly shown in Figure 4. When in this position 70 the switch is open, but when the lever 31 is moved forward by the actuating cable 33 the switch arm 46 will be moved past the vertical axis of the contact 43, being drawn down into contact with the switch point 75 42 by the spring 47 that has one end connected with the switch arm 46 and the opposite end with the switch contact 43. When the switch is closed the bell will ring 80 arousing the occupants of the house and notifying them that someone is entering or is trespassing upon their property.

In use, the casing which resembles in appearance the stump of a tree is erected in a secluded place upon the property which is 85 to be guarded. The actuating cable 33 may be extended to any remote position from the casing and adjusted at a reasonable height from the ground by the gage bar 31, so as to obstruct the passage of trespassers upon the 90 property. Pressure exerted upon the actuating cable by the trespasser will move the lever 31 forward so as to release the hammer 26 which swings downwardly with sufficient force to discharge the cartridge 95 38 within the barrel 14. The barrel 14 is spaced to one side of the cable so that the cartridge will be discharged at approximately the same time when the trespasser is in the direct path of the bullet. Upon release of the actuating cable the lever 31 will be withdrawn by means of the coil 100 spring 35. At the same time the cartridge is discharged the switch arm 46 will be moved so that the coil spring 47 will draw 105 it downwardly closing the two switch contacts and ringing the bell which is disposed in any desirable place within the house upon the property. Thus it is obvious that a trespasser or burglar who comes in contact with the apparatus will either be injured or scared, while at the same time the 110 occupants in the house upon the property will be notified.

It is to be understood that the form of 115 my invention herewith shown and described, is to be taken as a preferred example of the same, and that certain changes in the shape, size, and arrangement of parts may be resorted to without departing from 120 the spirit of the invention or the scope of the subjoined claims.

Having thus fully described my invention, I claim:—

In a device of the character described, 125 the combination with a casing simulating the stump of a tree, of an upright within the casing and spaced from the wall thereof, a gun barrel passing through the upright in the casing, a firing pin associated 130

with the barrel, a resilient arm normally holding the pin in a retracted position, a hammer consisting of resilient longitudinal strips of metal having one end secured to 5 the upper end of the upright, a slotted head secured to the free end of the hammer and adapted to contact with the firing pin, a shelf surrounding the upper edge of the casing adjacent the top of the 10 upright, a lever pivoted to one side of the shelf and extending across to the opposite side, said lever engaging the slot of said

head to hold the hammer in a raised or firing position, spring means to prevent accidental displacement of the lever, and 15 tripping means for releasing the lever permitting it to swing downwardly to contact with said firing pin.

In testimony whereof, I have affixed my signature in the presence of two witnesses. 20

FRANCIS H. PHILLIPS.
